UNITED STATES PATENT OFFICE.

EDWARD M. BELL, OF GREENEVILLE, TENNESSEE.

BOTTLE-HOLDING RACK.

1,143,488.

Specification of Letters Patent. Patented June 15, 1915.

Application filed October 8, 1914. Serial No. 865,704.

To all whom it may concern:

Be it known that I, EDWARD M. BELL, a citizen of the United States, residing at Greeneville, in the county of Greene and State of Tennessee, have invented certain new and useful Improvements in Bottle-Holding Racks, of which the following is a specification.

The present invention appertains to improvements in bottle or vial holding devices or racks especially adapted for use in medicine cases wherein a series of bottles is usually arranged in juxtaposed relation, the object of these improvements being to so secure the said bottles as to insure against their breakage or the mutilation of their labels, while maintaining them easily accessible through the instrumentality of special actuating means for said bottles.

To the end of accomplishing the foregoing object, I provide a suitable frame which may be inserted in a carrying case, or elsewhere desirable, said frame having bottle engaging means movably mounted thereon and adapted upon movement in one direction to interlock the bottle or bottles in said frame, and upon movement in the other direction to actuate said bottle so as to cause the same to assume an accessible position for extraction, a locking element being included in the bottle engaging means and adapted to hold the bottle against unauthorized movement in the manner hereinafter described.

A particularly advantageous feature of the invention lies in the disposition of the aforesaid bottle engaging means whereby the same coacts with the bottle cork in such a manner as to insure against its displacement from as well as proper positioning in the bottle.

These and such other objects as may hereinafter appear are attained by the novel construction, combination and arrangement of parts to be hereinafter specifically described and claimed.

Reference will now be had to the accompanying drawing, forming a part of this specification, wherein:

Figure 1 is a perspective view of a medicine case embodying my invention. Fig. 2 is a vertical sectional view on the line 2—2 of Fig. 1, but on an enlarged scale, and showing more clearly the details of construction of the bottle engaging means, and in dotted lines the release position assumed by same when it is desired to extract the bottle.

Fig. 3 is a horizontal sectional view taken on the line 3—3 of Fig. 2. Fig. 4 is a vertical sectional view on the line 4—4 of Fig. 3. Fig. 5 is an enlarged perspective view of the 60 slideable bottle engaging member alone.

Throughout the following detail description, and on the several figures of the drawings, similar parts are referred to by like reference characters.

Referring to the drawing and describing this invention, the numeral 1 indicates a frame which is of rectangular shape and of any desired material practicable for the purpose, said frame being shown in Fig. 1 70 as disposed in a medicine carrying case 2 of conventional shape and construction. As customary, a case of this character is provided with a series of juxtaposed bottles or vials 3, each so positioned as to permit of 75 extraction from its carrying frame and the means by which said bottles are held in said frame and moved into extracting position forms the special subject-matter of the present improvements. The lower side member 80 1^a of the frame 1 is provided with a plurality of recesses or openings, one of which is designated in Fig. 2 by the reference character 4, and as usual the lower end of a bottle 3 is adapted to be inserted in said opening. 85

The upper end of the bottle is adapted to be held by special engaging means now to be described, said means consisting of a member 5, preferably of metallic material and as shown in Fig. 5 so stamped or cut and 90 bent as to form opposing lateral flanges 5^a slidably mounted in grooves 6 formed in the upper frame member 1^b.

It will be observed by reference to Fig. 2 that the grooves 6 are inclined and this is 95 for a particular purpose as will be more particularly pointed out in the following description.

The main body portion of the slideable bottle engaging member normally rests against 100 the bottle cork 7 and is formed at its rear portion with a depending flange 8 slightly curved or concaved to conform to the curvature of said cork.

Near the forward portion of the bottle engaging means is pivotally mounted an angularly shaped catch 9, one arm of which is adapted to interlock in a notch 10 formed in the upper frame member 1^b near its outer edge, as seen in Fig. 2.

The opposite arm of the catch 9 depends and interposed between said arm and the

rear wall of the recessed portion in which the sliding bottle engaging member is mounted, is the spiral spring 11 normally tending to hold the upper arm of the catch 5 in interlocked engagement with the notch 10 before mentioned.

10 Adjacent the catch 9 is pivotally mounted a releasing lever or trigger 12, said trigger extending through an opening 13 at the forward portion of the bottle engaging member in pendent position in front of the bottle cork so as to be readily accessible in extracting the bottle from its holding frame.

15 The upper portion of the trigger 12 is adapted to engage the lower arm of the angular catch 9 when said trigger is lifted, this operation disengaging the upper arm of the catch from the notch and releasing the tension of the spring 11 which actuates the bottle engaging member sliding it forwardly in the inclined grooves which latter cause the member to move upwardly away from the bottle cork while permitting its flange 8 to move the bottle outwardly at its upper portion 20 from the frame 1 into the released position shown in dotted lines in Fig. 2 where the bottle may be readily grasped and removed from the case.

25 In the insertion of the bottle, it will be understood that the lower end is first inserted into an opening 4 in the frame and with the cork engaged beneath the horizontal concave portion of the slidable member 5 the upper end of said bottle is pushed inwardly, the said member 5 compressing the spring 11 while the downward incline of the grooves in which it is mounted causes the bottle engaging member to exert pressure in a longitudinal direction of said bottle 30 interlocking the same in the frame when the bottle has assumed vertical position as shown by full lines in Fig. 2, at which position the catch 9 engages with the notch in the frame 1 and interlocks the bottle from accidental movement. Obviously the movement above described not only tends to clamp the bottle between the side members of the frame but holds the cork in position in the bottle neck and forcibly stops the bottle 35 properly.

40 As shown in Figs. 3 and 5 a flange 5^a of the slidable member is cut away so as to form a shoulder 5^b which coats with a pin 14 extending through the frame to limit outward movement and prevent displacement of the said slidable member.

45 It will be apparent from the foregoing description that when the frame is provided with a series of bottle engaging members such as hereinbefore described, the bottles will be held in their carrying frame quite rigidly so as to insure against their movement or likelihood of fracture and preventing mutilation of the labels on the bottles as well as holding the bottles against rotation

tending to turn the labels into a position where they would not be readily observable. In order to accommodate for slight differences in the size or lengths of the bottles as well as to effectually cushion the same in the clamping action, I preferably interpose between the bottom of the bottle and the bottom of the opening or recess 4, a resilient member 14, of rubber or other desired spring material.

70 75 It will be obvious moreover that slight changes in the details of construction and arrangement of parts hereinbefore described may be made without departing from the spirit of the invention and within the scope of the claims hereto appended.

Having thus described my invention, what I claim as new is:

1. In bottle holding means of the class described, the combination with a frame, of a bottle engaging means mounted in said frame for bodily movement, said frame having guiding means for causing said bottle engaging means to exert pressure against the bottle interlocking the latter in the frame.

80 90 95 2. In bottle holding means of the class described, the combination with a frame, of a bottle engaging member slidably mounted on the frame, the frame having guiding means for guiding the bottle engaging member whereby to cause movement of said member into contact with a bottle carried in the frame and locking the latter in the frame under pressure longitudinally of said bottle.

100 105 110 3. In bottle holding means of the class described, the combination with a frame, of a bottle engaging member slidably mounted on the frame, the frame having guiding grooves arranged at an incline with respect to the frame whereby to cause a clamping action upon movement of said member in one direction.

115 120 125 4. In bottle holding means of the class described, the combination with a bottle, of a frame including side members between which the bottle is interposed, a slidable member mounted on one of the side members of the frame in a position to engage one end of said bottle, the side member last mentioned having inclined grooves in which the slidable member is movable bodily whereby upon insertion of the bottle between the frame members the slidable member is caused to exert pressure longitudinally on the bottle tending to move the bottle cork into and locking said cork from displacement from the bottle.

130 135 5. In bottle holding means of the class described, the combination with a frame, of a bottle engaging means mounted in said frame for bodily movement, said frame having guiding means for causing said bottle engaging means to exert pressure against the bottle interlocking the latter in the frame, and a locking member intermediate

the bottle engaging means and the frame holding the engaging means in position in said frame.

6. In bottle holding means of the class described, the combination with a frame, of bottle engaging means mounted in said frame for bodily movement, said frame having guiding means for causing said bottle engaging means to exert pressure against the bottle interlocking the latter in the frame, a locking member intermediate the bottle engaging means and the frame holding the latter in position in said frame, and release means for disengaging the locking member from the frame to permit removal of the bottle therefrom.

7. In bottle holding means of the class described, the combination with a frame, of bottle engaging means mounted in said frame for bodily movement, said frame having guiding means for causing said bottle engaging means to exert pressure against the bottle interlocking the latter in the frame, a locking member mounted on said bottle engaging means and adapted to engage the frame to hold a bottle in position therein, and a trigger member engageable with the locking member for releasing the bottle engaging means to permit withdrawal of the bottle from the frame.

8. In bottle holding means of the class described, the combination with a frame, of bottle engaging means mounted in said frame for bodily movement, said frame having guiding means for causing said bottle engaging means to exert pressure against the bottle interlocking the bottle in the frame, a locking member intermediate the bottle engaging means and the frame holding the bottle in position in said frame, and means interposed between the bottle engaging means and the frame for actuating the

former upon release of the locking member to cause outward movement of the bottle.

9. In bottle engaging means of the class 45 described, the combination with a bottle, of a frame in which said bottle is adapted to be disposed, said frame having a recess in which one end of the bottle is adapted to be inserted, bottle engaging means mounted in 50 said frame and comprising a slideable member shiftable bodily, said member being formed with offstanding flanges, the frame aforesaid having guide grooves in which said flanges are disposed, a catch pivotally 55 mounted on the bottle engaging member and adapted to interlock with the frame aforesaid in normal position, a spring interposed between the bottle engaging member and the frame and coacting with the catch 60 to hold the latter in engagement with the frame normally, said spring tending to slide the bottle engaging member upon release of said catch, and a trigger adapted to disengage the catch from the frame to permit 65 actuation of the bottle engaging member by said spring for moving said bottle into extracting position.

10. In bottle holding means of the class 70 described, the combination with a frame, of a bottle engaging member slidably mounted on the frame, the frame having guiding grooves arranged at an incline with respect to the frame whereby to cause a clamping action upon movement of said member in 75 one direction, and means for preventing the displacement of the sliding member from the frame.

In testimony whereof I affix my signature in presence of two witnesses.

EDWARD M. BELL.
